W. J. HARVEY.

HACKSAW FRAME.

APPLICATION FILED JUNE 13, 1914.

1,113,118.

Patented Oct. 6, 1914.

UNITED STATES PATENT OFFICE.

WILLIAM J. HARVEY, OF FLINT, MICHIGAN.

HACKSAW-FRAME.

1,113,118.

Specification of Letters Patent.

Patented Oct. 6, 1914.

Application filed June 13, 1914. Serial No. 844,859.

To all whom it may concern:

Be it known that I, WILLIAM J. HARVEY, a citizen of the United States of America, residing at Flint, in the county of Genesee and State of Michigan, have invented certain new and useful Improvements in Hack-saw-Frames, of which the following is a specification, reference being had therein to the accompanying drawings.

10 This invention relates to a hacksaw frame that is adjustable for different lengths of blades, that is rigid even when fully extended and that is readily secured in adjusted position without the use of screws, clamps or 15 the like.

Another feature of the invention is the absence of any projecting parts which may be struck by the work when the saw is in use and thereby causing the frame to become 20 unfastened.

The invention consists in the matters hereinafter set forth and more particularly pointed out in the appended claims.

In the drawings, Figures 1 and 2 are 25 views of a saw frame that embodies features of the invention; Fig. 3 is a view in detail of one of the end frame members; Fig. 4 is a view in section taken on the line IV—IV of Fig. 1; and Fig. 5 is a sectional view 30 taken on the line V—V of Fig. 1.

Referring to the drawings, a main tubular member 1 has a longitudinal slot indicated at 2 extending from end to end thereof. A pair of locking rings 3 are adapted to be 35 mounted each on an end portion of the member 1, each having a downturned ear 4 that enters a notch 5 on one side of the groove and a corresponding outstanding lug 23 adapted to span the groove 2 when the ring 40 is turned so that the ear 4 is at the bottom of its engaging notch. These rings are preferably burred or chased to give good hand hold.

A pair of frame members 6 which may be 45 tubular or solid are bent to form rounded corners and to have a straight portion 7 that telescopes readily with the middle section 1, a spline 8 on each member not only stiffening it but also entering the longitudinal slot 2 of the central member. A notch 9 near the inner end of each spline may be engaged by a split stop ring 10 thereby preventing the withdrawal of the end member from the central member. Notches 11 at desired intervals in the spline are adapted to be engaged by the lugs 23 of the securing

ring whereby the end members may be locked at the desired interval apart in the main member. A T-fitting is secured on the outer end of each end member and is adapted to receive posts 12 and 13. The inner end portion of one of these is cut away and is provided with a stud 14 over the end of which a saw blade may be hooked. A cross pin 15 at the other end engages with notches 16 to lock the posts in desired angular relation to the frame. The other post 13 is likewise halved and provided with a saw stud 17 while its outer end is screwthreaded for the reception of a handle 18. A washer 19 with an inwardly projecting tongue 20 that engages a key-way in a screwthreaded portion has a projection 21 adapted to engage any one of a series of notches 22 in a companion T-fitting and thereby clamp the posts 75 in the desire angular relation to the frame.

As a result of this construction the frame may be quickly adjusted to fit any one of the standard length of saw blades and when so disposed is rigid and cannot collapse. 80 The disposition of the locking members is such that they are not displaced by accidental contact with work and there are no bolts or clamping screws to set up and to work loose.

Obviously, changes in the details of construction may be made without departing from the spirit of my invention and I do not care to limit myself to any particular form or arrangement of parts. 90

What I claim is:—

1. A hacksaw frame comprising a main tubular member having a longitudinal slot therein, a pair of frame members in telescopic engagement with the main member, 95 a spline on each frame member projecting through the slot of the main member and having notches therein, a pair of locking rings mounted on the main member and adapted to be turned into engagement each 100 with a notch of a spline, and means on the outer ends of the frame members for securing the hacksaw.

2. A hacksaw frame comprising a main tubular member having a longitudinal slot 105 from end to end thereof with notches in the margins of the slot adjacent the ends, a pair of split locking rings rotatable on the tubular member each provided with a depending ear adapted to engage a notch of the slot 110 and with an extending lug adapted to span the slot, a pair of frame members bent be-

tween their ends each in telescopic engagement with the tubular member, a spline on each frame member extending through the longitudinal slot and provided with notches 5 adapted to be engaged by a lug of a locking ring, and means on the ends of the frame members for detachably securing a hacksaw blade thereto.

3. A hacksaw frame comprising a main 10 tubular member having a longitudinal slot from end to end thereof with notches in the margins of the slot adjacent the ends, a pair of split locking rings rotatable on the tubular member each provided with a depending 15 ear adapted to engage a notch of the slot and with an extending lug adapted to span the slot, a pair of frame members bent be-

tween their ends each in telescopic engagement with the tubular member, a spline on each frame member extending through the 20 longitudinal slot and provided with notches adapted to be engaged by a lug of a locking ring, a pair of split stop rings adapted to embrace the tubular member and extend through a notch of a spline of a frame member, and means on the ends of the frame members for detachably securing a hacksaw blade thereto.

In testimony whereof I affix my signature in presence of two witnesses.

WILLIAM J. HARVEY.
